MOUNT FOR TELESCOPIC GUN SIGHTS

Harvey A. Williams and Peter A. Jung, Davison,
Mich.; said Jung assignor to said Williams

Application April 12, 1944, Serial No. 530,720

1 Claim. (Cl. 33—50)

The present invention relates to a mounting for a telescopic gun sight.

It is the general object of the invention to provide a telescopic sight mounting of such character that the telescope may be quickly and easily attached and removed from the gun without the use of any tools.

Another object of the invention is to provide a mounting of the type mentioned which will positively retain the telescope in accurate position against the thrust induced by the recoil of the gun, and which will distribute the recoil thrust in a desirable manner.

Another object of the invention is to provide a mounting of the type mentioned which will insure that the telescope, when removed and reinstalled, will return to its original position without the necessity of any adjustments or danger of loss of previous adjustments.

Another object of the present invention is to provide in a mounting of the type mentioned having a portion which normally remains on the gun when the telescope is removed, which portion is of such character that it will not interfere with the use of the standard or open sights when the telescope is removed.

Another object is to provide a mounting having a windage adjustment which is unaffected by removal and remounting of the telescope.

Other objects and advantages of the invention will become apparent from the following description, the accompanying drawing, and the appended claim.

In the drawing:

Figure 1 is a fragmentary side elevation of a hunting rifle provided with a telescopic sight mounted by means of the present invention.

Figure 2 is a fragmentary side elevation similar to Figure 1 showing the manner in which the telescope is installed on or removed from the gun.

Figure 3 is a horizontal section taken on the line 3—3 of Figure 1, showing a plan view of the mounting plate which is secured to the gun.

Figure 4 is a longitudinal section taken on the line 4—4 of Figure 3.

Figure 5 is a transverse section taken on the line 5—5 of Figures 1 and 4.

Figure 6 is a transverse section taken on the line 6—6 of Figures 1 and 4.

Figure 7 is a transverse section taken on the line 7—7 of Figure 4.

Referring to the drawing in which like numerals are employed to designate like parts in the several views, there is shown a portion of a rifle having a barrel 10, a receiver 11 and a stock

12. The gun is equipped with a telescopic sight of any desired or conventional construction mounted in the telescope tube 13.

The present invention resides in the means for securing the tube 13 to the gun, and this means comprises a mounting plate 15 secured to the gun and a pair of mounting elements 16 and 17 which are secured to the telescope tube 13 in longitudinally spaced relation thereon. The underside of the mounting plate 15 is so shaped as to fit and seat solidly upon the rear end of the barrel at the region indicated by the arrow 18 in Figure 1 and upon the forward end of the receiver at the region indicated by the arrow 19.

The upper surface of the receiver at 19 is a generally cylindrically curved surface and, therefore, a correspondingly curved recess indicated by the dotted line 14 is formed in the underside of the plate. The rear edge of the recess 14 defines a shoulder 21 which engages the rear edge of the receiver portion 19 and sustains the recoil thrust. The rearward end of the plate is also formed to fit and seat solidly upon the rearward end of the receiver at the region indicated by the arrow 20.

These undersurfaces or mounting pads must be specially shaped for each different gun model, but in all other respects the mounting means of the present invention will be the same for all models.

The forward end of the plate 15 is secured to the forward end of the receiver by means of a pair of screws 22 and 23 mounted in countersunk holes in the forward end of the plate and threaded into tapped openings in the receiver. The rearward end of the plate 15 is similarly secured to the

rearward end of the receiver by screw 24. By reason of the shoulder 21, the screws 22, 23, and 24 are not subject to a shear stress which would otherwise result from recoil of the gun. Once the mounting plate is properly positioned and secured, it need not be removed from the gun, even

when the telescopic sight is removed, as it is so constructed that it will not interfere with the use of the standard open sights, for the reason that it is relatively thin and its upper surface is flat and unobstructed by projections. As hereinafter pointed out, all of the securing means are located beneath the plane of its upper surface.

The forward end of the plate 15 is provided with a generally rectangular opening 26, the forward edge of which is undercut to provide a downwardly and forwardly inclined surface 27, thus forming a rearwardly projecting lip 28 at the forward edge of the opening.

A pair of windage adjusting screws 30 and 31 are threaded from either side through the mount-

ing plate and project into the opening 26, as best shown in Figures 3 and 5. After these screws have been adjusted to the desired point, they are locked against further movement by means of soft copper plugs 32 which are forced into the threads of the adjusting screws by means of a pair of longitudinally extended screws 33. This adjustment is not altered during removal or remounting of the telescopic sight.

As best shown in Figure 5, the mounting element 16 of the forward end of the telescope tube is in the form of a split, circular strap having a heavy base portion 36 secured to one end of the strap and an attaching projection 37 secured to the other end. A pair of screws 38 project through suitable countersunk openings in the projection 37 and are threaded into suitable tapped openings in the base portion 36 of the attaching element 16. It will be apparent that when the screws 38 are tightened the attaching element will be wrapped tightly about and solidly grip the telescope tube 13. It will be noted that the undersurface of the heavy base portion 36 seats upon the flat upper surface of the plate 15. By reason of the heavy construction of the base portion 36, tightening of the screws 38 will not distort the seating surface and consequently will not interfere with the accurate positioning of the axis of the telescope. To further insure against the lateral rocking of the attaching element 16, the undersurface of the base 36 is undercut slightly, as best shown at 39 in Figure 5, in order that the actual seating contact will occur only at the side edges 40 and 41.

Base portion 36 of the mounting element 16 is provided with a downward extension 42, best shown in Figures 3, 4, and 5, which extends into the opening 26 in the mounting plate 15, and the extension 42 is provided with a forward projection 43 adapted to underlie the lip 28. The upper surface of the projection 43 is provided with a flat surface lying at the same angle as that of the surface 27 when the mounting element is seated upon the plate 15.

It will be apparent that if the mounting element 16 is tilted in the manner shown in Figure 2, that the downward extension 42, with its projection 43, may be inserted beneath the lip 28. In order to permit the element to be advanced forwardly to its final position longitudinally of the gun, while in an inclined position such as that shown in Figure 2, the bottom portion of the base 36 is inclined upwardly at the region forwardly of the edge of lip 28, as best shown at 44 in Figure 4. Thus, when the element is swung in a clockwise direction, as viewed in Figure 4, until it seats solidly upon the plate 15, the upper surface of the forward projection 43 will solidly contact the undersurface 27 of the lip 28 in the manner shown in Figure 4.

As shown in Figure 5, the sides of the downward extension 42 fit snugly between the inner ends of the windage adjusting screws 30 and 31, which form positive abutments controlling the lateral location of the mounting element. The position of these screws is not changed during insertion or removal of the extension 42 from the opening 26. In order to facilitate insertion and removal, the sides 46 and 47 of the extension are provided with a very small degree of outward and upward taper. A one degree angle between the sides of the extension is sufficient for this purpose.

The rearward mounting element 17 is identical in construction to the mounting element 16 pre-

viously described, except that in place of the downward extension 42 of element 16 the rearward element 17 is provided with a downward extension 52 which is generally cylindrical in form.

- 5 The projection 52 is adapted to fit within a circular opening 53 formed in the rear portion of the mounting plate 15. A transverse bore 54 extending through the mounting plate partially intersects the opening 53 and receives a locking pin 55. One side of the locking pin is provided with a cut-away notch 56 of cylindrical form which, in one rotative position of the pin 55, corresponds to the cylinder defined by the walls of the opening 53. The downward extension 52 is 10 provided with a similar notch 58 at its rear side adapted to fit the cylindrical portion of pin 55 when the pin is rotated into its locking position illustrated in Figures 3 and 4. One end of the pin 55 is provided with an operating lever 60, and 15 the opposite end is provided with an annular groove 61 adapted to receive a set screw 62 which operates to prevent axial movement of the pin 55 without interfering with its rotation.

The parts are so constructed and arranged that when the operating lever 60 is rotated to the position shown in Figures 1, 3, and 4, the cylinder portion of the pin 55 tightly fits within the notch 58 in the downward extension 52, and forces that extension snugly against the forward portion of the opening 53 in the plate. In this position the pin 55 holds the base of the mounting element 17 solidly against the upper surface of the plate 15. When the lever and pin 55 are rotated clockwise, approximately 180° from the position shown 20 in Figures 1, 3, and 4, the notch 58 in the pin will release the downward extension 52 and permit upward removal of the mounting element 17 in the manner shown in Figure 2.

It will be noted that when the rear mounting 25 element 17 is lifted upwardly to remove the telescopic sight from the gun in the manner shown in Figure 2, that its initial movement is a pivotal movement about a point in the vicinity of the forward mounting element 16. Consequently it 30 is necessary to slightly relieve the back edge of the opening 53 in the mounting plate 15 in order to prevent interference between the plate and the downward extension 52.

The plate 15 is preferably made as a single 35 plate in the manner illustrated. One side of the plate is cut away as indicated generally at 65 in Figures 2 and 7, at a point intermediate its ends, and is also undercut as indicated in 66 in Figure 7 in order to provide clearance for ejection of 40 spent shells. It is advantageous to use a single plate for both mounting elements as it facilitates installation of the plate in accurate alignment with the bore of the gun and also positively distributes the recoil thrust between both mounting elements. It is apparent, however, that, if desired, the central connecting portion of plate 45 15 can be omitted and the two end portions separately secured to the gun without departing from the spirit of the invention.

45 It is apparent that there is provided, in accordance with the present invention, a mounting which positively locks the telescopic sight in an accurate position in which the recoil thrusts are taken by fixed, solid abutments, namely, shoulder 50 21, the inclined surface 27 and the forward wall of the opening 53. This position is not disturbed in any way by removal and reinstallation of the telescope sight because none of the positioning means is disturbed during such removal or reinstallation. The holding devices tightly hold the 55

mounting elements against the top surface of the plate 15 in such a manner that they cannot rock or be displaced in any direction. The cam 55 is so constructed as to bind frictionally in the position shown in Figure 4 to prevent accidental displacement of the telescope. It is further apparent that the telescope can be removed very quickly, without the use of any tools, by merely flipping the handle upwardly, lifting the rear end of the sight upwardly, and then withdrawing the projection 43 from beneath the lip 28. The telescope is returned to mounting position by reverse movement. No strains are imposed on the telescope tube itself in either operation.

Any initial inaccuracies in the alignment of the plate 15 may be corrected by the windage screws 30 and 31. These screws provide a permanent adjustment which is not disturbed after the first installation of the sight, because the

telescope itself contains a windage adjustment which is sufficient for actual windage corrections.

What is claimed is:

5 A mounting for a telescopic sight for a gun including a mounting element adapted for attachment to the telescope tube adjacent one end thereof, a mounting plate adapted for attachment to a gun, said plate having a rearwardly projecting undercut lip, said element having a downwardly and forwardly projecting hooklike portion having an upper surface adapted to engage the undersurface of said lip, a pair of aligned windage adjustment screws threaded from opposite sides into the edges of said plate and engaging opposite sides of said hooklike portion and means for preventing displacement of the opposite end of the telescope tube.
